UNITED STATES PATENT OFFICE.

DAVID HINDAHL, OF CHICAGO, ILLINOIS, ASSIGNOR TO RODGER BALLAST CAR COMPANY, OF CHICAGO, ILLINOIS, A CORPORATION OF MAINE.

RAILWAY DUMP CAR.

Application filed August 27, 1926. Serial No. 131,871.

This invention relates to railway dump cars, to-wit: cars designed for carrying lading in subdivided form, and which, for the sake of adapting them to discharge their lading by gravity, have certain portions of their bottom surfaces consisting of doors movable to open or closed position at will, and other portions thereof in the form of inclines which direct the material to the doors and insure substantially complete evacuation in response to the mere act of opening the doors.

One object of the present invention is to provide an improved assembly between side walls, transverse bottom frame members, and side wall inclines, whereby the said elements may stand in mutually sustaining relation each to the others. Accordingly, one feature of the invention consists in constructing the transverse bottom frame members from channel section beams, placed with their webs vertical and their flanges horizontal, riveting gusset plates to the backs thereof as well as to the stakes at the sides of the car, and providing the side incline plates of the hopper bottom with vertical end flanges which overlap the faces of the channel members opposite to those faces which receive the gusset plates, as well as overlapping the gusset plates and stakes; the outer ends of the horizontal flanges of the channel members being cut away to receive the said flanges on the incline plates, and said incline plate flanges being riveted to all of said parts and constituting angle braces which stiffen the joints between them, resistance of stresses being mainly in the plane of the incline plate. A further feature incident to this part of the invention relates to the castings which provide the pintle bearings for the main doors and the bearers for the shafts which wind the lifting chains of doors, said casting being produced with a pair of cheeks providing a pair of spaced bearings for the door pintle; a broad upwardly presented face by which the casting bears beneath and is secured to the body of the car, terminating in a bevel through which it bears against and is riveted to a side incline of the hopper bottom; and an upstanding flange through which the casting is riveted to the vertical web of the channel-shaped cross member; the broad upper face being formed with a trough-like depression providing an upwardly opening elongated bearing in which the chain-winding shaft lies, and a substantial opening being formed through the said upstanding flange, in line with the chain-winding shaft bearing, that facilitates introduction of said shaft.

In cars of the type described, for the sake of rendering them selective as to deposit of their lading, doors have been provided, specially constructed to permit of opening in different ways, to-wit, in a manner to discharge lading to either side of the track at will, or between the rails of the track, or simultaneously in both positions; but difficulty has been experienced from the circumstance of portions of the lading entering between hinging parts and parts upon which they are mounted, especially when the door is hinged adjacent a hopper wall from which it projects as a guiding surface when open. A further object of the invention is to provide a novel construction of door, for instance, an auxiliary or secondary door, and particularly the construction of the means whereby it is mounted upon or articulated with its support, for instance, the main door, with a view to preventing the accumulation of lading or foreign matter at the point of articulation, and thus avoiding difficulty in bringing the auxiliary door to its fully closed position, as well as saving its hinge from deterioration. In realizing this part of the invention, the surface-forming plate of the door is provided with a tail-piece continuing beyond the door pintle and curved concentrically therewith to avoid interference with hinging action, and a plate, for instance, the main door plate located between the stationary hopper wall and the auxiliary door plate, is lapped upon the tail-piece and auxiliary door plate, in protecting relation thereto. Preferably the castings are secured beneath the main door plate to provide pintle bearings for the auxiliary door,

and these are recessed back of their pintle assembly of the sides and bottoms of the cars 65 bearings to admit the curved tail-piece of the auxiliary door when the door is closed, thereby avoiding the necessity for shortening the tail-piece to an undesirable extent; and the tail-piece itself may be provided with a recess of dimension corresponding approximately to the thickness of the pintle 70 castings in order that it may be given even 10 a greater protecting dimension on either side of the casting.

In the accompanying drawings, in which the preferred embodiment of the several features of the invention is shown by way of 15 illustration—

Figure 1 is a side elevation of those portions of a railway car with which the invention is immediately concerned, to-wit, one end of the car, together with sufficient of the 20 intermediate portion thereof to show its bottom dumping facilities.

Figure 2 is a vertical transverse section on the line 2^x—2^x of Figure 1.

Figure 3 is a detail view, on an enlarged 25 scale, of a portion of Figure 2, showing the protected hinge of the auxiliary door.

Figures 4, 5, and 6 are, respectively, a top 30 plan view, a side elevation, and an outer end view of one of the two castings which appear in the outer lower portions of Figure 2 and which provide the pintle bearings for the main doors and the bearings for the chain winding shafts of the auxiliary doors.

Referring to Figure 1, 1 represents a side 35 wall, 2 an end wall, and 3 the wheels, suggesting truck location, of a railway car of known general design and for application to which the several features of the present invention are primarily intended. Cars of this type have heretofore been provided with bottom dump doors 4 of special construction, to be hereinafter alluded to, end inclines 5 for directing material to the space longitudinally inward from the trucks, where the 45 bottom dump doors are necessarily located, and lateral bottom inclines 6 (Fig. 2) for directing material laterally inward to the door openings and past the spaces occupied by the door mountings.

As will be seen in Figure 2, cars of this type are constructed with a central longitudinal center sill 7 and transverse under 50 frame members 8 resting thereon and suitably united therewith, as, for instance, through means of the brackets 9; which said center sill, through that portion of its length which traverses the dumping area and defined by the length of the bottom doors 4, is made to carry center slope plates 10.

Underframe members and side bracing.

It has always been a problem, in gondola cars or cars of the type with which this invention deals, to develop secure and lasting

with their bracing members, and the present invention takes advantage of functional members or members concerned with the operation of the car, in the development of improved conditions in this part of the car, by 70 making the transverse member of the under-frame or bearer 8 of channel section, with its web 8^a vertical and its flanges 8^b and 8^c horizontal; riveting the ends of the said bearer to the stakes 15; riveting the gusset members 16 not only to the stakes 15, as usual, but also directly to the channel members 8 and preferably to the backs of said channel members; cutting away the ends of the horizontal flanges 8^b, 8^c of the channel member, as shown in Figure 2; and causing vertical attaching flanges 6^a on the lateral hopper inclines 6 to lap upon and to be riveted directly to the web 8^a and to the stake 15 while maintaining the inclination 75 which the side inclines 6 are required to have in service, and therefore, in a position which causes the inclined plates to serve as effective angle braces between the sides and the transverse underframe members, and, in such service, to receive stresses which are largely in the planes of the plates and therefore in the direction to be resisted most effectively.

In cars of the kind described, it has heretofore been proposed to mount doors, such as 4, upon pintles, such as 4^a, located beneath the side hopper-inclines 6, and, to this end, provide castings 17 in which to mount said pintles and, incidentally, when doors 4 have been of the type employing doors 18 pivoted on the main doors at 19, it has been proposed to design the castings 17 so that they will afford bearings for shafts 20 upon which to wind chains 21 for control of said auxiliary doors. The present invention improves the design for the casting 17 by forming it with a broad bearing plate 17^a by which it bears beneath the body of the car, for instance, the bottom marginal member 21 of the side 1; with an upwardly presented intermediate flange 17^b by which the casting is riveted to the back of the web 8^a of the underframe cross member 8; with a beveled bearing face 17^c through means of which the casting meets and is riveted to the side incline 6 or the guard piece 22, as shown in Figure 2; with two cheek members 17^d, depending from the top plate and constructed with aligned openings that provide pintle bearings 4^a; with transverse depression 20^a in the top plate 17^a, providing an upwardly opening bearing for shaft 20; with the two transverse web-members 17^e, 17^f, which are integral with the top plate 17^a and cheek member 17^d, and in planes parallel with and adjacent the respective bearings 4^a, 20^a to strengthen them, and with

a bracket web 17^a depending in a central plane and extending from web member 17 to the outer end of the casting.

Auxiliary door construction.

In cars of the kind described, it is desirable to utilize, in addition to the main door 4 pivoted at 4^a and having its lower inner free end controlled by shaft 23, the auxiliary door 18, articulated with the main door at 19, which is about the point where the center inclines 10 meet the auxiliary door. At such point, difficulty has been experienced as a result of lading entering between the fixed and movable parts of the articulation, also from deterioration of the hinge. To remedy this defect, the present invention provides the bottom plate of the door 18 with a tail piece 18^a extending inwardly beyond the pintle 19 to an extent which adapts it to effectively shield the pintle and its bearing, said tail piece being curved concentrically with the pintle in order not to interfere with the swinging of the door; and to make the shield still more effective, the plate 4^b of the main door 4 is continued outwardly in overlapping relation to the plate of the auxiliary door 18 and the tail piece 18^a, and to a point of intersection with the center incline 10, so that, as shown more clearly in Figure 3, the articulating connection of the auxiliary door is thoroughly protected. This protection is effected not only against lading or residue thereof or foreign matter traversing the center incline 10 when the auxiliary door is open to the dotted line position of Figure 3, but it is equally effective when the main door 4 is open, as a whole, upon its pivot 4^a, as by turning the shaft 23, and in which position lading will traverse the entire surface of the main door 4, made up in part of the auxiliary door 18 and the main door plate 4^b, since at this time the auxiliary door 18, held tightly to its closed position, is bearing snugly against the lapped end of the plate 4^b.

I claim:

1. In a hopper bottom car, a transverse bottom frame member having a vertical web, a dump door, and a pintle bearing casting for mounting said dump door in controlling relation to the hopper bottom; said casting being formed with an upwardly presented seating face and a vertical flange overlapping and attached to the web of the frame member.

2. In a hopper bottom car, a bottom frame member having a vertical face, a dump door, and a pintle bearing casting for mounting said dump door in controlling relation to the hopper bottom; said casting being formed with an upwardly presented seating face and a vertical flange lapping upon and attached to the vertical face of the frame

member; said casting also having a depression in its said seating face, providing an upwardly opening shaft-bearing, and said attaching flange having an opening above the plane of said seating face and in registry with said shaft bearing, facilitating introduction of a shaft into said bearing. 70

3. In dump car construction, members providing a hopper bottom, a door for controlling discharge from said bottom, and a pintle bearing casting for mounting said door; said casting comprising a pair of spaced cheek members constructed with aligned openings to receive a pintle bearing, an upwardly presented face through which the casting enters into bearing against the car body, a recess extending downwardly from said upper face and providing an upwardly open control-shaft bearing, and an upwardly extending attaching flange in a vertical plane intermediate of said cheek members, provided with a recess extending above the said face in vertical registry with the open shaft bearing, and facilitating the introduction of a shaft 85 thereinto. 90

4. In combination with a hopper bottom car having a body member and an inclined bottom member, a pintle bearing casting having a portion constructed with an upwardly presented face through which it is secured to the body member, and a diagonal portion through which it is secured to said inclined bottom member. 95

5. A pintle bearing casting for the doors of hopper bottom cars; said casting comprising an upwardly presented face through which it seats against a body member of the car, and a diagonally presented face adapting it to meet and be secured to the side 105 incline member of a hopper bottom.

6. A pintle bearing casting for the doors of hopper bottom cars; said casting comprising an upwardly presented face through which it seats against a body member of the car; an upwardly presented flange through which it is lapped upon and secured to a vertical face of the car structure, and a diagonally presented face adapting it to meet and be secured to the side incline member of a hopper bottom. 110 115

7. A pintle bearing casting for the dump doors of hopper bottom cars; said casting comprising a broad top plate having a horizontal portion through which it is adapted to be secured to a portion of the car body; said casting having in an intermediate plane of its top plate an upwardly presented lapping flange for securing it to a vertical surface of the car structure, and having, in spaced vertical planes beneath said top plate, cheeks constructed to provide the pintle bearing. 120 125

8. A pintle bearing casting for the dump doors of hopper bottom cars; said casting 130

- comprising a broad top plate having a horizontal portion and a diagonal portion through which it is adapted to be secured, respectively, to a portion of the car body and to an incline thereof; said casting having in an intermediate plane of its top plate an upwardly presented lapping flange for securing it to a vertical surface of the car structure, and having, in spaced vertical planes beneath said top plate, cheeks united by said horizontal and diagonal portions and constructed to provide the pintle bearing.
9. A pintle bearing casting for the dumping doors of hopper bottom cars, said casting comprising a horizontal top plate designed for application to a car structure, cheeks depending in spaced vertical planes from said top plate and constructed with a pintle bearing, and an upwardly opening depression in said plate extending from cheek to cheek and providing a cradle bearing for a shaft.
10. A pintle bearing casting for the dumping doors of hopper bottom cars, said casting comprising a top plate designed for application to a car structure, a portion depending from said top plate constructed to provide a pintle bearing, said plate having an upwardly opening depression providing a cradle bearing for a shaft, and a flange extending upwardly from said plate, crossing said cradle bearing and having an opening in vertical registry therewith.
11. In a dump car, a pintle bearing casting comprising a top plate, a depression in said top plate providing a shaft bearing, cheek members depending from said top plate, and cross webs in planes adjacent the sides of said depression, integrally uniting said cheek members.
12. In a dump car, a pintle bearing casting comprising a top plate, a depression in said top plate providing a shaft bearing, cheek members depending from said top plate, and cross webs in planes adjacent the sides of said depression, integrally uniting said cheek plates; said cheek members having near the plane of one of said cross webs, aligned openings providing a pintle bearing.
13. In a dump car having swinging doors, a door pintle casting, comprising a top plate, a pair of cheek members depending from said top plates, a pintle bearing extending through said cheek members, and a transverse web member integral with the top plate and the cheek members, located in a plane adjacent said pintle bearing.
14. In a dump car having swinging doors, a door pintle casting, comprising a top plate, a pair of cheek members depending from said top plate, a pintle bearing extending through said cheek members, and a transverse web member integral with the top plate and the cheek members, located in a plane adjacent said pintle bearing; said top plate being formed with a shaft bearing in a plane on one side of said web member.
15. In a dump car having swinging doors, a door pintle casting, comprising a top plate, a pair of cheek members depending from said top plate, a pintle bearing extending through said cheek members, and a transverse web member integral with the top plate and cheek members, located in a plane adjacent said pintle bearing; said top plate being formed with a shaft bearing in a plane on one side of said web member; and said casting having a second transverse web integral with the top plate and cheek members located in a plane on the opposite side of the shaft bearing from the web member first named.
16. In a dump car having hinging doors, a pintle bearing casting, comprising a top plate, cheek members depending from said top plate, a pintle bearing extending transversely through said cheek members, a transverse web member integral with said top plate and cheek members, and an attaching flange upstanding from the top plate in a plane parallel with the cheek members, and intersecting the plane of the web member.
17. In dump car construction, a door having a hinge and comprising a plate formed with a tail piece extending into protecting relation to the hinge, and a pintle casting mounting said door and having a recess receiving said tail piece.
18. In dump car construction, a deflecting wall, a discharge door pivoted adjacent to said wall, comprising a plate which intersects the plane of the deflecting wall, and a stationary plate extending from the side of the pivot of the door opposite to that on which the door lies, and which also intersects the plane of said wall and overlaps upon the plate of the door.
19. In dump car construction, a deflecting wall, a door having a hinge adjacent said wall, comprising a plate in a plane intersecting the plane of the wall and terminating in a tail piece which embraces the hinge, and a stationary plate extending from the side of the hinge opposite to the door, through the plane of the wall, and overlapping the tail piece and the plate of the door adjacent thereto.
20. In dump car construction, a hinged door, a pintle casting providing a support for the hinge of the door, a door plate constructed with a tail piece which encircles the hinge, said casting being recessed to receive the tail piece, and a stationary plate extending across the tail piece and the recessed portion of the casting.
21. In dump car construction, a hinged door, a pintle casting providing a support for the hinge of the door, and a door plate.

constructed with a tail piece which embraces the hinge; said casting being recessed to receive the tail piece, and said tail piece being recessed to receive the casting.

5 22. In dump car construction, a hinged door, a pintle casting providing a support for the hinge of the door, and a door plate constructed with a tail piece which embraces the hinge; said casting being recessed to re-

ceive the tail piece and said tail piece being recessed to receive the casting, and there being a plate which extends across the recessed casting and tail piece and laps upon the door plate.

Signed at Chicago, Illinois, this 23rd day ¹⁰ of August, 1926 ¹⁵

DAVID HINDAHL.
